(57) **CLAIM**

(21) Appl. No.: **29/297,131**

The ornamental design for the tail light assembly for an automobile, as shown and described.

(22) Filed: **Nov. 5, 2007**

(30) **Foreign Application Priority Data**

May 3, 2007 (DE) 4 07 02 335

DESCRIPTION

(51) **LOC (9) Cl.** **26-06**

FIG. 1 is a plan view onto the tail light assembly for an automobile, showing my new design;

(52) **U.S. Cl.** **D26/28**

FIG. 2 is a top view thereof;

(58) **Field of Classification Search** D26/28-36;

FIG. 3 is a right-side view thereof; and,

362/459-468, 475-478, 485-487

FIG. 4 is a left-side view thereof.

See application file for complete search history.

The figures of the drawing show a left-hand tail light assembly; the right-hand tail light assembly is a substantial mirror image of the illustrated assembly.
